UNITED STATES PATENT OFFICE

THEODORE S. DOWST, OF CHICAGO, ILLINOIS, ASSIGNOR TO DOWST MANUFACTURING COMPANY, OF CHICAGO, ILLINOIS, A CORPORATION OF ILLINOIS

PACKING STRUCTURE

Application filed May 20, 1930. Serial No. 453,914.

This invention relates to a support and package providing structurally and functionally improved characteristics over devices of this character as heretofore constructed.

It is an object of the invention to provide a package and method of packing by means of which one or more articles may be readily assembled and shipped, and in which during shipment, the likelihood of breakage will be reduced to a minimum, aside from the fact that after shipment, the articles will be readily accessible for display and other purposes.

A further object of the invention is that of providing a method of packing and a structure whereby such method may be practiced and which structure may be provided largely by means of automatic machinery, and when so provided may be employed by relatively unskilled labor to efficiently package articles for display, storage and shipping purposes.

With these and further objects, in mind, reference is had to the attached sheet of drawing illustrating one practical embodiment of the invention, and in which:

Fig. 1 is a plan view of a package with the cover broken away to disclose the underlying construction;

Fig. 2 is a transverse sectional view along the line 2—2 and in the direction of the arrows of Fig. 1;

Figs. 3 and 4 show respectively the bottom and top blanks employed in the package; and

Figs. 5 and 6 are enlarged sectional views taken along the lines 5—5 and 6—6, and in the direction of the arrows of Figs. 3 and 2 respectively.

In the foregoing figures, the invention has been illustrated in connection with packaging articles such as toys in the nature of miniature furniture. At this time, it will be understood that while the invention may be employed to advantage in this connection, that the present method of packaging and display is not necessarily limited to this use, but may advantageously be employed in connection with the packaging of any number of different types of articles.

Thus as in Figs. 1 and 2, the numeral 10

indicates the base of a receptacle which is completed by a cover 11. As aforeslated, the present structure has been devised for packaging articles such as a miniature furniture set including for example a range 12, 55 chair 13, cabinet 14 and table 15, all of these having been indicated in dotted lines. These are supported upon a base 16 as illustrated in Fig. 3 which has a series of flaps 17 proportional in area to the several articles which are 60 to be supported. The base 16 may be spaced from the base of the receptacle in any desired manner. One convenient method of accomplishing this is that of providing extended portions 18 forming a part of the base and 65 bent to furnish flanges bearing against the base of the receptacle to thus space the deck 16 therefrom. A retaining member is furnished by employing a sheet of material 19 having cut-out portions 20 corresponding generally in contour to the outline of the objects supported upon the deck 16, and extending into certain of these cut out portions are flaps 21 which may in turn be slotted to define subsidiary flap portions 22. 75

In order to maintain the retaining sheet in association with the deck or base 16, any suitable spacing means may be furnished to retain the sheet a predetermined distance from the cover. For example, as shown, extended portions 23 may form a part of the sheet 19 and be bent upwardly as in Fig. 2 to engage the under face of the cover 11 to assure this result. 80

Thus, with the articles arranged upon the 85 deck or base 16, and after the latter is disposed within the receptacle base or body 10, it will be obvious that an attractive display is afforded. In this connection, it will be understood that the base may have an upper 90 layer of material 24 which may present a certain decorative effect, and this layer may be slotted as at 25 in order to facilitate and permit of the several parts of the base being bent to extend at angles with respect to each other. 95 Obviously, in such position and as has been indicated, portions of the articles will extend beyond the lower edges of the flaps 17 and underlie the lower face of the deck 16. However, the spacing of this deck from the base 100

10 is sufficiently great to prevent these extended portions contacting with the base. If now, the retaining member is applied, it will be observed that the articles will extend 5 through the openings 20 thereof and thus these articles will be locked against upward movement. Additionally, by virtue of the flaps 21 and the subsidiary flaps 22, a displacement of the articles along substantially 10 horizontal planes is prevented incident to the fact that these flaps will define what might be termed framing portions to prevent this occurring as has been clearly illustrated in Figs. 1 and 2. At this time, it will also be 15 observed that the projecting portions 23 may be formed with tabs 26 so that after the retaining member is applied, it may be readily removed when desired.

Now with the cover of the receptacle in 20 position, the retaining member will be forced into virtually clamping engagement with the articles, and the base or deck 16, this occurring incident to the spacing expedient provided by the extended portions 23 or the 25 equivalent thereof. In such position, the various articles are supported in a cushioned manner against shocks in all directions and a displacement of these articles is prevented. Accordingly, the package may be stored or 30 shipped and subjected to all reasonable rough usage without either danger of damage to the enclosed articles or displacement thereof, and accordingly, the package may be opened and the retaining element removed in order to 35 attractively display the articles.

From the foregoing, it will be understood that among others the several objects of the invention as specifically aforeoutlined are achieved. It will moreover be appreciated 40 that numerous changes in the construction and rearrangements of the parts might be resorted to without departing from the spirit of the invention as defined by the claims.

Having described my invention, what I 45 claim as new and desire to secure by Letters Patent, is:

1. A packing for articles including, in combination, a receptacle, a deck within and spaced from the base of said receptacle, flaps 50 forming a part of said deck and to be depressed below the plane of the same, articles disposed upon said deck and bearing against said flaps to extend below the deck, and retaining means bearing against said articles to 55 maintain them in contact with and against displacement with respect to said flaps, said retaining means comprising a sheet formed with cut-out portions of an area such as to frame at least portions of the articles.

2. A packing for articles including, in combination, a receptacle, a deck within and spaced from the base of said receptacle, flaps 60 forming a part of said deck and to be depressed below the plane of the same, articles disposed upon said deck and bearing against

said flaps to extend below the deck, and retaining means bearing against said articles to maintain them in contact with and against displacement with respect to said flaps, said retaining means comprising a sheet formed 70 with cut-out portions of an area such as to frame at least portions of the articles, flaps extending into said cut-out portions, and said flaps overlying said articles.

3. A packing for articles including, in combination, a receptacle, a deck within and spaced from the base of said receptacle, flaps forming a part of said deck and to be depressed below the plane of the same, articles disposed upon said deck and bearing against 80 said flaps to extend below the deck, and retaining means bearing against said articles to maintain them in contact with and against displacement with respect to said flaps, said retaining means comprising a sheet formed 85 with cut-out portions of an area such as to frame at least portions of the articles, flaps extending into said cut-out portions, and said flaps presenting frame portions encircling 90 portions of said articles.

4. A packing for articles including, in combination, a receptacle, a deck within and spaced from the base of said receptacle, flaps forming a part of said deck and to be depressed below the plane of the same, articles disposed upon said deck and bearing against 95 said flaps to extend below the deck, retaining means bearing against said articles to maintain them in contact with and against displacement with respect to said flaps, said retaining means comprising a sheet formed with cut-out portions of an area such as to frame at least portions of the articles, flaps extending into said cut-out portions, said flaps presenting frame portions encircling 100 portions of said articles, and subsidiary flap portions bearing against said articles and preventing their displacement with respect to 105 said framing portions.

5. A packing for articles including, in combination, a receptacle, a deck within and spaced from the base of said receptacle, flaps forming a part of said deck and to be depressed below the plane of the same, articles disposed upon said deck and bearing against 110 said flaps to extend below the deck, retaining means bearing against said articles to maintain them in contact with and against displacement with respect to said flaps, said retaining means comprising a sheet formed with cut-out portions of an area such as to frame at least portions of the articles, flaps extending into said cut-out portions, said flaps presenting frame portions encircling 115 portions of said articles, a cover for said receptacle, and means cooperating with said cover and said retaining means to prevent a displacement of the latter with respect to the former.

6. A support for an article including in 120

combination, a receptacle, a deck within said receptacle and being spaced from the base thereof, a rectangular opening in said deck having one side spaced from the base of said 5 receptacle, and having the opposite side provided with a tongue extending at an angle to one side of the plane of said deck, and a retaining member in contact with said deck, having a rectangular opening above the opening in said deck, and having a tongue extending at an angle to the other side of the plane of said deck, portions of said article being supported between said tongues and a side of the opening in said deck.

15 In testimony whereof I affix my signature.
